UNITED STATES PATENT OFFICE.

FRANK H. OPFERGELT, OF WOODSTOCK, ILLINOIS.

WELL-BORING APPARATUS.

1,118,575.

Specification of Letters Patent. Patented Nov. 24, 1914.

Application filed December 10, 1913. Serial No. 805,708.

To all whom it may concern:

Be it known that I, FRANK H. OPFERGELT, a citizen of the United States, residing at Woodstock, in the county of McHenry and State of Illinois, have invented certain new and useful Improvements in Well-Boring Apparatus, of which the following is a full, clear, concise, and exact description, reference being had to the accompanying drawings, forming a part of this specification.

My invention relates to well-boring apparatus, particularly apparatus for preventing the earth surrounding a hole from caving in while the hole is being bored. The apparatus employed for this purpose comprises a plurality of sheet metal pipes or cylinders adapted to be connected together, and I contemplate the provision of novel means for securing the adjacent sections together.

The apparatus which I provide is particularly useful in boring drainage wells, and I shall illustrate my said apparatus as used in sinking such a drainage well.

In the accompanying drawings illustrating my invention—Figure 1 is a view, partly in section and partly in elevation, illustrating the apparatus of my invention employed in sinking a drainage well; Fig. 2 is a fragmentary view illustrating two cylinders adapted to be secured together, this view illustrating the securing means in detail; Fig. 3 is a cross-sectional view taken on the line 3—3 of Fig. 1, and Fig. 4 is an enlarged fragmentary detail view illustrating how the plates constituting the fastening device are secured to the sheet metal pipes or cylinders.

Similar reference numerals refer to similar parts throughout the several views.

In boring a drainage well, I utilize an auger of any suitable type, such, for instance, as the one shown in the drawings at 4, the operating rod to which the auger handle is attached being made in sections adapted to be connected by couplings 5 or other suitable securing means, in order that the rod may readily be made longer as the bored well becomes deeper. After boring down to a certain depth (the depth varies in different localities) I usually find that the earth will cave into the hole being bored unless some means is provided to prevent it.

In order to prevent the earth from caving

into the hole, I provide a plurality of metal pipes or cylinders 6, preferably constructed of galvanized iron. In the top of each one of the cylinders 6 is a pair of diametrically-opposite apertures 7, through which a rod or bar 8 may be passed. It is to be noted that each of the cylinders 6 is of greater diameter than the hole which the auger is capable of boring, and consequently some considerable force must be exerted upon a cylinder to force it down into the ground. This is accomplished by passing the bar 8 through the apertures in the top of the cylinder, turning the cylinder and at the same time pressing downwardly upon the bar. It will be seen that the cylinder which has been forced into the hole will effectually prevent the surrounding earth from caving into the hole being bored. As the depth of the hole or well becomes greater it is necessary to utilize more of the cylinders, the cylinders being disposed with the lower end of one overlapping the top of the cylinder immediately therebeneath, as clearly shown in Fig. 1.

Adjacent ends of the cylinders 6 are secured together by novel fastening devices shown most clearly in Figs. 1 and 2. Secured to each of the cylinders is a metal plate 9 provided with a plurality of tongues 10. Each of the plates 9 is disposed a slight distance from the top of its supporting cylinder in order that the cylinder immediately thereabove may overlap, the plates 9 being riveted in position, as shown. The plates 9 are beveled at 12, 13 and 14 for a purpose to be presently made apparent. Secured by rivets to the lower end of each of the cylinders except the one first sunk into the ground is a plate 15 which is provided with notches 16 arranged to receive the tongues 10 of the plates 9. The plates 16 are beveled at 17, 18 and 19, as illustrated.

When the cylinders 6 are being forced down into the ground the same are turned by means of bar 8 in the direction of the arrow in Fig. 1, and at the same time are forced downwardly. It will be seen that inasmuch as only beveled edges of the locking plates are presented to the earth as the cylinders are forced down and turned, much less exertion is required than would be the case if the beveled edges were not provided. It will be noted, however, that the edges 20 of the plates 15 are not beveled. Earth pass-

ing against the unbeveled edges of the plates 15 serves to force them into engagement with their associated locking plates 9.

In sinking a hole or well, I find it desirable to keep the bottom of the lowermost pipe or cylinder slightly below the bottom of the hole, as illustrated in Fig. 1. I am thus enabled to prevent water from collecting in the hole being bored. It will be noted that 10 inasmuch as the cylinders, as they are forced downwardly, are turned in the direction indicated by the arrow, the locking plates of each pair will be held tightly together.

When the cylinders 6 are to be removed, a 15 bail 21 may be attached to the rod or bar 8 and then by means of a rope 22 passing over a pulley or pulley and winch, the cylinders are drawn out of the ground. As the cylinders are raised, the bar 8 is manipulated to 20 turn the cylinders in the direction indicated by the arrow, thus holding the locking plates of each pair in tight engagement with each other. The rope 22 may, of course, be directly attached to the bar 8 if desired.

25 It is desirable that the ends of the rivets by means of which the locking plates are held in position be flush with the inside surfaces of the cylinders and the outer surfaces of the locking plates. It is a simple matter 30 to countersink the outer ends of the rivets in the locking plates, as shown in the drawings, and in order to have the inner ends of the rivets flush with the inner surfaces of the cylinders, I notch the inner surfaces of the 35 locking plates and force the portions of the cylinders under the rivet heads into said notches, as is clearly illustrated in Fig. 4 of the drawings.

From the above, it will be seen that I have 40 provided means whereby the earth surrounding a bored well may be prevented from caving in while the well is being bored, and moreover, that the auger used in boring the well may be lowered into the hole, manipulated therein, and withdrawn through the cylinders, as often as is necessary.

In practice I find it desirable to provide each pair of connected pipes or cylinders with two locking devices, located on diametrically opposite portions of the pipes or cylinders. I have not thought it necessary 50 to show more than one locking device at each joint.

What I claim as new and desire to secure 55 by Letters Patent of the United States is:

1. Well-boring apparatus comprising a plurality of cylinders adapted to be disposed in superposed relation and to have their adjacent ends overlap, and locking devices for securing adjacent ends of the cylinders together, each of said locking devices comprising a pair of plates, one carried at the lower end of one cylinder and the other plate carried by the upper end of an adjacent overlapping cylinder, said plates com-

prising coöperating tongues and notches, the first-mentioned plate having its upper and lower edges beveled and the edge thereof opposite said tongues and notches unbeveled, the other plate having its upper and 70 lower edges beveled and its edge opposite said tongues and notches beveled.

2. Well-boring apparatus comprising a plurality of cylinders adapted to be disposed in superposed relation, and locking devices adapted to retain adjacent cylinders together, each of said locking devices comprising a pair of locking plates having co-acting tongues and notches, one locking plate of each pair being secured to the lower 75 end of one of said cylinders, and the other locking plate of each pair being secured to the upper end of an adjacent cylinder.

3. Well-boring apparatus comprising a plurality of cylinders adapted to be disposed in superposed arrangement, and locking devices for securing adjacent cylinders together, each of said locking devices comprising a pair of plates having coöperating tongues and notches, one plate of each pair 90 being secured to the lower end of one of the cylinders and the other plate of the pair being secured to the upper end of the cylinder immediately therebeneath, together with means for moving said cylinders longitudinally of their common axis and for turning said cylinders upon their common axis.

4. Well-boring apparatus comprising a plurality of cylinders adapted to be disposed in superposed arrangement, locking devices 100 for securing adjacent cylinders together, each of said locking devices comprising a pair of plates having coöperating tongues and notches, one plate of each pair being secured to the lower end of one of said cylinders and the other plate being secured to the upper end of a cylinder immediately 105 therebeneath, together with means for forcing the cylinders into the ground and turning the same to hold the locking plates of 110 each pair in tight engagement with each other.

5. Apparatus of the class described comprising a plurality of sheet metal cylinders adapted to be disposed in superposed arrangement, locking devices for securing adjacent cylinders together, each of said locking devices comprising a pair of plates having coöperating tongues and notches, and means for forcing the cylinders into the 115 ground and for turning them upon their common axis, said plates being so conformed that only beveled edges thereof are presented to the earth when the cylinders are turned therein or moved longitudinally of 120 their common axis in the earth.

6. Apparatus of the class described comprising a pair of cylinders adapted to be disposed in superposed arrangement with the lower end of the upper cylinder over 130

lapping the upper end of the lower cylinder, and means for securing said cylinders together comprising a pair of locking plates, one of said plates carried by each of said cylinders and said locking plates being provided with coöperating tongues and notches.

7. Apparatus of the class described comprising a plurality of cylinders adapted to be disposed in superposed arrangement, 10 means for forcing said cylinders into a hole to prevent the surrounding earth from caving into the hole, and means for securing adjacent cylinders together, each of said securing means comprising a pair of locking 15 plates having coöperating tongues and notches.

8. Apparatus of the class described com-

prising a plurality of cylinders adapted to be disposed in superposed arrangement, and means for securing adjacent cylinders together, each of said securing means comprising a pair of plates having coöperating tongues and notches, said plates being so conformed that only beveled edges thereof are presented to the earth when the cylinders are moved longitudinally of their common axis or are rotated on their axis. 20 25

In witness whereof, I hereunto subscribe my name this 4th day of December, A. D. 1913.

FRANK H. OPFERGELT.
